(57) **CLAIM**

The ornamental design for INFLATABLE NECK PILLOW as shown and described.

DESCRIPTION

FIG. 1 is a top view of an INFLATABLE NECK PILLOW in accordance with the new design in a deflated state;

FIG. 2 is a front view thereof;

FIG. 3 is a bottom view thereof;

FIG. 4 is a left side view thereof in an inflated state;

FIG. 5 is a top view thereof in an inflated state shown in a use configuration;

FIG. 6 is a right view thereof in an inflated state;

FIG. 7 is a rear view thereof in an inflated state;

FIG. 8 is a bottom view thereof in an inflated state;

FIG. 9 is a bottom perspective view thereof in an inflated state;

FIG. 10 is a bottom perspective view thereof in an inflated state shown in use configuration with environment.

The dotted broken lines shown in FIGS. 1, 3, 6, 5, 8, 9, and 10 depict portions of the inflatable neck pillow that form no part of the claimed design. The dotted broken lines in FIG. 10 depict environment of a person that forms no part of the claimed design.

The dashed broken lines shown in FIGS. 2, 4, 6, 7, 9 and 10 depict stitching and form a part of the claimed design.

1 Claim, 10 Drawing Sheets
